UNITED STATES PATENT OFFICE.

WAINWRIGHT B. GERVAIS, OF CHICAGO, ILLINOIS, ASSIGNOR TO VARIETY MANUFACTURING COMPANY, OF CHICAGO, ILLINOIS, A CORPORATION OF ILLINOIS.

COUNTERBALANCED FIRE-SHUTTER.

1,353,333.

Specification of Letters Patent. Patented Sept. 21, 1920.

Application filed August 20, 1917. Serial No. 187,130.

To all whom it may concern:

Be it known that I, WAINWRIGHT B. GERVAIS, a citizen of the United States, and a resident of Chicago, in the county of Cook 5 and State of Illinois, have invented a certain new and useful Improvement in Counterbalanced Fire-Shutters, of which the following is a full, clear, concise, and exact description, reference being had to the accompanying drawings, forming part of this specification. 10

My invention relates to counter-balanced fire shutters.

Heretofore it has been customary to 15 counter-balance a rolling fire shutter with a coil spring mounted in the drum of the shutter. Such manner of counter-balancing the shutter has a number of disadvantages. It is difficult to construct a counter-balancing 20 spring which will follow the law of action of the rolling shutter and will counter-balance the weight of the same throughout the entire travel. It is a familiar fact that in the spring-balanced rolling shutters the spring 25 will counter-balance the shutter when it is up or when it is down but that in the middle part of the movement of the shutter the curtain is not properly counter-balanced.

The spring after it is once installed in the 30 drum is difficult to manipulate. The strength and resiliency of spring made even under identical conditions are variable.

According to my invention springs are 35 entirely dispensed with and the curtain is exactly counter-balanced at every position or condition. Consequently the curtain may be moved with a minimum of effort. The counter-balancing mechanism which I employ is of the type which will cause the shutter to close automatically if the operating 40 parts of the counter-balancing mechanism are broken or become unfastened.

I shall now describe a particular embodiment of my invention to teach those skilled 45 in the art how to practice the same.

In the accompanying drawings which form a part of the present specification—

Figure 1 is a front elevational view of a device embodying my invention;

50 Fig. 2 is a section taken on the line 2—2 of Fig. 1; and

Fig. 3 is an end elevational view of the same.

The rolling shutter 1 consists of a plural- 55 ity of metal flaps hinged together and se-

cured at the inner end to a drum, not shown, which drum is fastened to the shaft 2. The shaft of the drum has bearings in the heads 3 and 4 of the generally cylindrical casing 5.

The lower end of the shutter 1 is provided 60 with the flanges 6, preferably formed of angle iron. The bottom flanges of the angle iron 6 are cut away and the edges of the curtain 1 run in suitable guides 7 upon each side of the door. These guides 7 preferably 65 form continuations of the heads 3 and 4 of the casing 5 as is understood in the art. Suitable handles 8 are fastened on the end of the curtain 1 for operating the same.

The law of operation of the shutters is as 70 follows:

When the shutter is extended to the bottom then the weight W of the shutter operates with a certain lever arm r . When the shutter is rolled up on the drum the diameter of the drum has been increased by the amount of curtain rolled thereupon so that the radius has changed to R . The weight which operates to unbalance the curtain has been decreased by the amount which has been 80 rolled upon the drum so that the weight may now be represented by w , consequently the turning effect upon the drum may be represented when the curtain is down by the quantity $W \cdot r$. When the shutter is rolled to 85 its open position the force acting to unbalance the shutter may be represented by the quantity $w \cdot R$.

Inasmuch as the curtain rolls up gradually and consequently loses weight gradually and 90 the drum diameter increases gradually, it can be seen that a straight line law governs the unbalanced condition of the shutter.

In order to properly counter-balance this condition a counter-balancing device having a similar straight line law of action is provided in the spiral pulley 9 and weight 10. The cable 11 is fastened to the pulley 9 and the weight 10 lies in a bight of the cable 11, the upper end of the cable being attached to a suitable support. The support which I have illustrated comprises a hook 12 pivoted at 13 and held against movement by a fusible link 14.

In the event of destruction of the fusible 105 link 14 or destruction of the cable 11, the weight 11 would be taken off of the cable, thus removing the counter-balancing influence and permitting the curtain 1 to drop.

It is to be understood that when the cur- 110

tain is rolled up the unbalancing force of the curtain is less than when the curtain has been unrolled. The weight 10 operates on a shorter radius arm than when the curtain is unrolled. Consequently a very nice counter-balance is secured at all times.

While I have described the counter-balance as operating on a straight line law of action, it is to be understood that the weight 10 and pulley 10, 9 may be made to compensate for any type of unbalanced load by causing the groove in the pulley 9 to follow the desired variation. It is further to be understood that in practice the weight 10 is provided with a well or chute and that the pulley 9, instead of being connected directly to the shaft 2 and the drum of the curtain, may be geared thereto. I do not intend to be limited to the precise details shown and described.

I claim:

1. In combination, a rolling shutter normally unbalanced by the unrolled portion of the shutter, a shaft operatively secured to said shutter, a spiral pulley connected to said shaft, a cable or the like secured to the spiral pulley and wrapped thereupon, a weight slidably resting in a bight of said cable and fusible means anchoring the free end of the cable.
2. In combination, a rolling shutter, said shutter being normally unbalanced by the unrolled portion of the same, a shaft operatively connected to said shutter, a pulley having different portions of different diameters connected to said shaft, a cable or the like wrapped on said pulley, thermally releasable means holding the end of the cable and a weight connected to the cable by a pulley lying in a bight of the cable.
3. In combination, a rolling shutter normally unbalanced by the unrolled portion of the shutter, a shaft operatively secured

to said shutter, a pulley having a spiral groove connected to said shaft, a cable or the like in said spiral groove, a counterbalancing weight on said cable, thermally releasable means holding the cable, said counterbalancing weight setting up a turning moment on said shaft varying with the varying positions of the door to counterbalance the same in the normal operation thereof, said cable being adapted to release the counterbalancing influence of said counterbalancing weight upon destruction of said thermally releasable means.

4. In combination, a rolling shutter normally unbalanced by the unrolled portion of the shutter, a shaft operatively secured to said shutter, a spiral pulley connected to said shaft, a cable or the like secured to the spiral pulley and wrapped thereupon, a weight suspended by a bight in the cable, fusible means anchoring the free end of the cable, said cable being adapted to release the weight upon destruction of said fusible means.

5. In combination, a shaft, a rolling shutter operatively secured thereto, vertically arranged guide means for guiding said shutter in its vertical movement, a counterbalancing weight setting up a turning moment on said shaft varying with the varying vertical positions of said rolling shutter to effectively counterbalance the same throughout the various positions along said vertically arranged guide means and thermally controlled means for releasing the counterbalancing influence of said counterbalancing weight, permitting the door to close unimpeded by the action of said counterweight.

In witness whereof, I hereunto subscribe my name this 16th day of August, A. D. 1917.

WAINWRIGHT B. GERVAIS.
